(57) **CLAIM**

The ornamental design for an energy dissipation device for seismic protection of engineering structures as shown and described.

DESCRIPTION

FIG. 1 is a perspective view of an energy dissipation device for seismic protection of engineering structures embodying the design according to the present invention;

FIG. 2 is a front view of the device according to the present invention;

FIG. 3 is a rear view thereof;

FIG. 4 is a right side view of the device according to the present invention;

FIG. 5 is a left side view thereof;

FIG. 6 is a top plan view of the device according to the present invention; and,

FIG. 7 is a bottom plan view thereof.
